UNITED STATES PATENT OFFICE.

WILHELM MOLLER, OF PHILADELPHIA, PENNSYLVANIA, ASSIGNOR, BY MESNE ASSIGNMENTS, TO EASY-PAN GREASING MACHINE CO., INC., OF NEW YORK, N. Y., A CORPORATION OF NEW YORK.

PAN-GREASING MACHINE.

Application filed December 5, 1924. Serial No. 754,073.

To all whom it may concern:

Be it known that I, WILHELM MOLLER, a citizen of the United States, residing at Philadelphia, in the county of Philadelphia and State of Pennsylvania, have invented certain new and useful Improvements in Pan-Greasing Machines, of which the following is a specification.

My invention relates to machines for greasing pans, such as disclosed in Letters Patent of the United States No. 1,532,256, granted me April 7, 1925.

The objects are to provide novel means, for feeding grease to the pan greasing brushes, which may be repaired or taken apart without interfering with the brushes and their operating mechanism, and to which access may be readily had.

These objects, and other advantageous ends which will be described hereinafter, I attain in the following manner, reference being had to the accompanying drawings in which—

Figure 1 is a side elevation of a pan greasing machine having my invention applied thereto,

Figure 2 a section on line 2—2 of Figure 1,

Figure 3 a section on line 3—3 of Figure 2,

Figure 4 a section on line 4—4 of Figure 2,

Figure 5 a section on line 5—5 of Figure 2, and

Figure 6 an enlarged section on line 6—6 of Figure 1.

Referring to the drawings, 1 indicates a frame of suitable construction having a compartment 2, 3 a motor mounted in the compartment, 4 a reduction unit connected with the motor, 5 mechanism connected with the reduction unit for transforming rotary motion to reciprocating harmonic motion, 6 a rack connected with the mechanism and slidably mounted in suitable bearings, and 7 pan greasing brushes geared to the rack and mounted in step bearings 8 adjustably mounted on guides 9 secured to the frame. The step bearings are adjusted by screws 10 suitably connected therewith and the frame. The above mechanism is described more in detail in my patent referred to above.

My improved grease feeding means is

mounted on the frame and is adapted to feed grease to the brushes by manipulating a pedal. It consists of grease conduits, each made up of a curved pipe 11 secured to a T 12 connected by a flexible hose 13 with a pump 14 in a grease tank 15. When pump 14 is operated, it will suck grease from the tank and force it through the conduit onto the greasing brush 7. The conduit is normally positioned so that it will not interfere with the pans to be greased as they are slid over the brushes. When it is desired to feed grease to the brushes, the pipes 11 are swung into position adjacent the brushes as shown in Figure 2.

The mechanism for swinging the pipes to this position consists of a rocker shaft 16 mounted in suitable bearings on the machine, sleeves 17 slidably keyed to the rocker shaft 16 and having stems 18 to which T's 12 are secured, an arm 19 secured to the shaft, a rod 20 having one end pivoted to arm 19 and the other end 21 loosely connected with a pedal 22 preferably by bending the end of the rod under the end 23 of the pedal, and a compression spring 24 mounted between a collar 25 on the rod and a guiding bracket 26 on the frame. As pedal 22 is pressed downward it will allow compression spring 24 to lift rod 20, rock shaft 16 and swing pipes 11 into position adjacent the greasing brushes so that grease may be fed from the pump through the grease conduit onto the brushes.

The mechanism for operating the pump consists of a rod 27 passing through guiding bracket 26 and having one end pivoted to the pedal and the other end loosely connected preferably by a pin and slot connection with a pump actuating lever 28 pivoted at 29 and connected with the pump plungers 30 at 31, and a compression spring 32 for restoring the pump and pipes 11 to their idle position. Spring 32 is preferably mounted between guiding bracket 26 and a collar 33 on rod 27.

To feed grease to the brushes, the pedal 22 is pressed downward and released to allow the parts to be moved to their idle position. The first part of the downward movement of the pedal allows rod 20 to be moved upward by spring 24, which is normally under compression, until a stop 34

engages the under side of guiding bracket 26. Rod 20, through the arm 19, rocker shaft 16 and sleeves 17, swings pipes 11 to a position adjacent the brushes. Due to the pin and slot connection between the upper end of rod 27 and the pump actuating lever 28, the first part of the downward movement of pedal 22 does not operate the pump but merely compresses spring 32. A 10 further downward movement of the pedal further compresses spring 32 and operates the pump, through the pump actuating lever 28, to force grease through hoses 13, T's 12 and pipes 11 onto the brushes. Due to the 15 loose connection between the end 21 of the rod and end 23 of the pedal this latter downward movement of the pedal does not affect the pipes 11.

When the pedal is released, spring 32, 20 being under compression, will raise the pedal and bring the parts to their former idle position. Spring 32, being heavier than spring 24, will compress spring 24 so that when the pedal is again operated spring 24 25 will swing pipes 11 into position adjacent the brushes.

In order to keep each pipe 11 in proper alignment with its brush when the brushes are adjusted by the screws 10, I connect a 30 yoke 35 with each step bearing 8 preferably by a stud bolt 36. The ends of each yoke 35 are provided with eyes 37 which are disposed at the opposite ends of sleeves 17 and through which the rocker shaft 16 passes. 35 When the step bearings 8 which carry the pan greasing brushes are adjusted, the sleeves which carry pipes 11, being slidably keyed to the rocker shaft, will be moved with the step bearings and thus keep the 40 pipes 11 in proper alignment with the greasing brushes.

The grease feeding means above described may be repaired or taken apart without affecting the brushes or their operating mechanism.

While I have described my invention as taking a particular form, it will be understood that the various parts may be changed without departing from the spirit thereof, 50 and hence I do not limit myself to the precise construction set forth, but consider that I am at liberty to make such changes and alterations as fairly come within the scope of the appended claims.

55 Having thus described my invention, what I claim as new and desire to secure by Letters Patent is:—

1. In a pan greasing machine having a 60 grease pump and greasing brushes; grease conduits connected with the pump and movably mounted on the machine, and means for moving the conduits adjacent the brushes and for operating the pump to feed grease through the conduits onto the brushes.

65 2. In a pan greasing machine having a

grease pump and greasing brushes; grease conduits connected with the pump and swingably mounted on the machine, and means for swinging the conduits adjacent the brushes and for operating the pump to 70 feed grease through the conduits onto the brushes.

3. In a pan greasing machine having a 75 grease pump and greasing brushes mounted for adjustment toward and from each other; grease conduits connected with the pump and movably mounted on the machine; means connecting each brush with a conduit whereby an adjusting movement of the brush will be imparted to the conduit, and means for 80 moving the conduits adjacent the brushes and for operating the pump to feed grease onto the brushes.

4. In a pan greasing machine having a 85 grease pump and greasing brushes; a rocker shaft mounted on the machine; grease conduits keyed to the shaft and connected with the pump, and means for rocking the shaft and for operating the pump to feed grease onto the brushes.

90 5. In a pan greasing machine having a grease pump and greasing brushes mounted for adjustment; a rocker shaft mounted on the machine; grease conduits slidably keyed 95 on the rocker shaft and connected with the pump; means connecting the conduits with the brushes whereby an adjusting movement of the brushes will slide the conduits on the rocker shaft, and means for rocking the shaft and for operating the pump to feed 100 grease onto the brushes.

6. In a pan greasing machine having a 105 grease pump and greasing brushes; grease conduits connected with the pump and movably mounted on the machine; a pedal; means connected to the pedal and the conduits, and means connected with the pedal and the pump, whereby a movement of the 110 pedal will move the conduits adjacent the brushes and operate the pump to feed grease through the conduits onto the brushes.

7. In a pan greasing machine having a 115 grease pump and greasing brushes; grease conduits connected with the pump and movably mounted on the machine; a pedal; means connected to the pedal and the conduits, and means connected with the pedal and the pump, whereby a part movement of the 120 pedal will move the conduits adjacent the brushes without operating the pump and further movement of the pedal will operate the pump without moving the conduits.

8. In a pan greasing machine having a 125 grease pump and greasing brushes; a rocker shaft mounted on the machine; grease conduits keyed to the shaft and connected with the pump; a pedal; means connecting the 130 pedal with the rocker shaft, and means connecting the pedal with the pump whereby a movement of the pedal will rock the shaft.

- to bring the conduits adjacent the brushes and operate the pump to feed grease through the conduits to the brushes.
9. In a pan greasing machine having a grease pump and greasing brushes; a rocker shaft mounted on the machine; grease conduits secured to the shaft and connected with the pump; a pedal mounted on the machine; an arm on the rocker shaft; a rod having one end pivoted to the arm and the other end loosely connected with the pedal; another rod pivoted to the pedal and loosely connected with the pump; resilient means for moving the first mentioned rod to rock the shaft and bring the conduits adjacent the brushes when the pedal is moved to operate the pump, and resilient means for bringing the pedal and the parts connected therewith to their idle position.
10. In a pan greasing machine having a grease pump and greasing brushes; a rocker shaft mounted on the machine; sleeves slidably keyed to the shaft; stems on the sleeves; a grease conduit secured to each stem and connected with the pump, and means for 25 rocking the shaft to bring the conduits adjacent the brushes and for operating the pump to feed grease through the conduits to the brushes.
11. In a pan greasing machine having a grease pump and greasing brushes mounted for adjustment; a rocker shaft mounted on the machine; sleeves slidably keyed to the shaft; conduits secured to the sleeves and connected with the pump; means connected with the brushes including a yoke having its ends disposed at opposite sides of the sleeves whereby an adjusting movement of the brushes will be imparted to the sleeves, and means for moving the rocker shaft to bring 35 the conduits adjacent the brushes and for operating the pump to feed grease through the conduits onto the brushes.
12. In testimony whereof I have signed my name to this specification.

WILHELM MOLLER.
